CLAIM

The ornamental design for a pot with egg cracker, as shown and described.

DESCRIPTION

FIG. 1 is a perspective view of my ornamental design for a pot with egg cracker;

FIG. 2 is a front elevational view of the design shown in FIG. 1;

FIG. 3 is a rear elevational view of the design shown in FIG. 1;

FIG. 4 is a side elevational view of the design shown in FIG. 1, the opposite side of which is a mirror image;

FIG. 5 is a top plan view of the design shown in FIG. 1;

FIG. 6 is a cross-sectional view taken along lines 6—6 in FIG. 5; and,

FIG. 7 is a bottom plan view of the design shown in FIG. 1. The broken lines represent portions of the structure and form no part of the claim.
